ART OF CRACKING HYDROCARBONS

Application filed October 27, 1927. Serial No. 229,099.

This invention relates to improvements in the cracking of high-boiling and easily cracked hydrocarbon oils, such as heavy gas oil and pressed wax distillate, for the production of gasoline. In order to maintain a high rate of production from a given installation, it is usually desirable to carry out such cracking operations for the production of gasoline at relatively high cracking temperatures. 10 The heavier and higher boiling hydrocarbon oils, such as those just mentioned, tend to decompose with the formation of excessive quantities of gas and carbon or heavy pitch at cracking temperatures, and this tendency 15 is more pronounced as the cracking temperature increases. In pressure distillation processes in particular, this tendency involves several objectionable incidents which increase the difficulty of cracking such stocks and 20 which make such stocks less desirable as raw material for the production of gasoline. This invention relates particularly to improvements in the cracking of such high-boiling and easily cracked hydrocarbon oils by distillation under pressure and provides an improved method of operation in which difficulties, such as those just mentioned, are avoided or minimized.

According to the present invention, the 30 high-boiling easily cracked stock is subjected to the cracking conditions of temperature and pressure maintained in the cracking operation in admixture with a low-boiling refractory stock, and the mixture is proportioned so 35 that sufficient heat is absorbed in vaporization of the low-boiling refractory stock to avoid objectionable over-cracking, with excessive formation of gas or carbon or heavy pitch, of the high-boiling easily cracked 40 stock. A maximum proportion of the heat so absorbed in vaporization of the low-boiling refractory stock is in turn absorbed in fresh stock supplied to the operation so that this heat is not permitted to escape. This last 45 mentioned heat recovery is advantageously carried out by direct heat exchange between the fresh stock and the vapors from the cracking operation with condensation and return in admixture with the fresh stock of a maximum proportion of the vaporized low-boil-

ing refractory stock. In addition to the fresh high-boiling easily cracked stock, additional low-boiling refractory stock is supplied as the operation proceeds to maintain optimum conditions, particularly with respect to over-cracking of the high-boiling easily cracked stock. 55

In carrying out the invention, thus, a low-boiling refractory stock is maintained in cyclic circulation through a heating zone, a vaporizing zone and a refluxing operation and the volume of this low-boiling refractory stock in such circulation is maintained by the supply of additional low-boiling refractory stock during the operation as this stock escapes as part of the distillate product. Under some conditions, this low-boiling refractory stock may in part be cracked and to this extent escape as part of the cracked product. Hydrocarbon oils not less than 70 90% of which boil off up to 550° F. are particularly advantageous low-boiling refractory stocks for use in carrying out this invention. To eliminate or reduce further vaporization of the low-boiling refractory stock 75 in the vaporizing zone and refluxing operation, the vaporizing zone and refluxing operation are maintained under superatmospheric pressure, advantageously under a pressure approximately the same as that at 80 which the hot oil products are discharged from the heating zone. The high-boiling easily cracked stock to be cracked is introduced into direct contact with vapors in the refluxing operation. The heavier components of the vapors including a maximum proportion of the low-boiling refractory stock is thus condensed at the same time that the fresh stock is preheated by this heat exchange. The resulting oil mixture including the reflux condensate and the unvaporized fresh stock is then circulated to the heating zone. The heat absorbed in the heating zone in vaporization of the low-boiling refractory stock to protect the high-boiling easily 85 cracked stock against over-cracking is thus returned, at least in large part, to the cracking operation proper. In the heating zone, the oil mixture is heated to a suitable cracking temperature under a suitable pressure, 90

say to 725-775° F. under a pressure in the neighborhood of 80-120 pounds per square inch, to effect the desired cracking. The pressure in the heating zone should not exceed a value beyond which vaporization of the low-boiling refractory stock in the heating zone at the prevailing temperature in the heating zone is insufficient to have the desired protective effect in avoiding over-cracking of the high-boiling easily cracked stock. From the heating zone the hot oil products are discharged into the vaporizing zone and from the vaporizing zone the resulting vapors escape to the refluxing operation and unvaporized oil is discharged in the usual way. The vapors uncondensed in the refluxing operation are taken off and condensed to form a distillate product including the cracked gasoline product and a part of the low-boiling refractory stock. The high-boiling easily cracked stock to the treatment of which the invention particularly relates are those hydrocarbon oils not more than 50% of which boil off up to 600° F. During the operation, the low-boiling refractory stock is supplied at an average rate maintained in excess of 5% of the total rate at which fresh stock is supplied and the high-boiling easily cracked stock is supplied at the average rate maintained in excess of 50% of the total rate at which fresh stock is supplied, excluding that amount of oil required initially to charge the still system. Thus with a total rate of feed of 1200 gallons per hour, the rate of supply of low boiling oil would be supplied at a rate in excess of about 60 gallons per hour while the high boiling oils would be supplied at a rate in excess of about 600 gallons per hour, for example. In general, the more easily cracked the high-boiling stock, the larger is the percentage of the low-boiling refractory stock fed to the still. The cracking conditions maintained in the operation may also be reduced in severity with more easily cracked stocks, but in general it is advantageous to increase the proportion of low-boiling refractory stock supplied to the operation at least up to the point where heat loss becomes excessive.

One form of apparatus adapted for carrying out the process of the invention is illustrated diagrammatically and conventionally in the accompanying drawings. These drawings represent, partly in section and partly in elevation, with parts broken away, a pressure still of the general type described and illustrated in Letters Patent No. 1,285,200 issued to the Sinclair Refining Company, November 19, 1918 on the application of Edward W. Isom.

The pressure still illustrated comprises the bulk supply drum 1, a bank of heating tubes 2, arranged in the heating flue of a furnace 3, and circulating connections 4, 5 and 6, in-

cluding a circulating pump 7, for circulating oil from the bulk supply drum upwardly through the heating tubes and back to the bulk supply drum. A reflux tower 8 is arranged above the bulk supply drum. Vapors escape from the bulk supply drum through vapor line 9, into the lower end of the reflux tower. Vapors remaining uncondensed escape from the upper end of the reflux tower through vapor line 10 to the condenser 11. This condenser is arranged to discharge into the receiver 12 from which the distillate product is discharged through connection 13 and uncondensed vapors and gases through connection 14. The pressure in the system may be maintained and regulated by means of valve 15 arranged in the vapor line between the reflux tower 8 and the condenser 11, or by means of suitable valves arranged beyond the condenser or receiver. Connection 16 is provided for the introduction of fresh stock into the upper end of the reflux tower 8. The oil mixture collecting in the lower end of the reflux tower 8 may be supplied to the circulating still charge through connection 17 or may be forced into the circulating still charge through connections 18, 19 and 20 by means of pump 21. Additional fresh stock may be supplied to the circulating still charge through connections 22 and 20 by means of pump 23. Connection 24 is provided for discharging pitch-laden oil or tar from the bulk supply drum 1 during operation. Connection 25 is provided for initially charging the still and for pumping out the still at the end of a run. Cool oil for example a part of the fresh stock is supplied through connection 26 for cooling and lubricating the bearings of the circulating pump. Part of the fresh stock may thus be supplied to the circulating still charge through the pump bearings. The exposed parts of the still system including the reflux tower 8, the bulk supply drum 1, the circulating connections 4, 5 and 6, are advantageously lagged or thermally insulated.

In carrying out the invention in a still system of the type illustrated, the still is initially charged with say about 8,000 gallons of gas oil and brought to cracking conditions of temperature and pressure in the usual way. If the stock to be cracked has a particularly marked tendency toward over-cracking, the initial still charge, instead of being made up of this stock, may consist of some more refractory stock, say an ordinary gas oil. After the still is brought to operating conditions of temperature and pressure, vapors are taken off through the reflux tower to the final condenser and the introduction of fresh oil through connection 16 is begun. The refluxing operation carried out in tower 8 for example, may with advantage be controlled by regulating the rate at which fresh stock is supplied through connection 16. About the

same time, or shortly thereafter, the discharge of pitch-laden oil or tar through connection 24 is begun. As reflux condensate together with unvaporized fresh stock accumulates in the lower end of the reflux tower it is returned to the circulating still charge either through connection 17 or connections 18, 19 and 20. The latter mode of operation is particularly advantageous as it provides for positive forcing, by means of pump 21, of the oil mixture from the reflux tower into the oil stream entering the heating tubes 2. The low-boiling refractory stock and the high-boiling easily cracked stock may be supplied during the operation either separately or in admixture. For example, the high-boiling stock may be supplied entirely through connection 16 except for a small part supplied through connection 26 and the low-boiling stock supplied through connection 22. Or, a mixture of the high-boiling and low-boiling stocks in appropriate proportions may be supplied through connection 16, any additional low-boiling stock required being supplied through connection 22. Although the proportion of low-boiling stock in mixtures supplied through connection 16 may be increased to increase the refluxing action in the tower it is usually advantageous to limit the proportion of low-boiling stock supplied through connection 16, or to avoid the introduction of low-boiling stock through this connection, to reduce or eliminate any heat loss due to vaporization of such low-boiling stock in the reflux tower.

While the invention is of special value and application in connection with the operation of pressure stills of the type illustrated, it is also useful in connection with the operation of pressure stills in which unvaporized oil is not returned from the vaporizing zone to the heating zone. A suitable apparatus for carrying out this latter embodiment of the process of the invention might be illustrated, for example, by removing the circulating connection 4 in the apparatus illustrated and suitably closing the connections left open by the removal of this circulating connection.

I claim:

An improved method of cracking high-boiling easily cracked hydrocarbon oils, of which not more than 50% boil off up to 600° F. at atmospheric pressure, for the production of gasoline, which comprises maintaining in cyclic circulation through a heating zone, a vaporizing zone and a refluxing operation all under superatmospheric pressure a low-boiling refractory stock, introducing the high-boiling easily cracked stock to be cracked into direct contact with the vapors in the refluxing operation and circulating the unvaporized part of this high-boiling stock preheated by the heat exchange in the refluxing operation to the heating zone in admixture with reflux condensate from the re-

fluxing operation, heating the oil mixture to a cracking temperature under a superatmospheric pressure low enough to permit vaporization of the low-boiling refractory stock at the maximum temperature to which the oil mixture is heated, circulating the vapors separated in the vaporizing zone to the refluxing operation, discharging unvaporized oil from the vaporizing zone, taking off from the refluxing operation and condensing a vapor mixture including vapors of the low-boiling refractory stock and of the cracked gasoline product, and supplying a low-boiling refractory stock not less than 90% of which boils off up to 550° F. to the oil mixture circulating to the heating zone, the average rate of supply of the low-boiling refractory stock not less than 90% of which boils off up to 550° F. being maintained in excess of 5% and the average rate of supply of the high-boiling easily cracked stock not more than 50% of which boils off up to 600° F. being maintained in excess of 50% of the total rate at which fresh stock is supplied during the operation excluding initial charge.

In testimony whereof, I have subscribed my name.
